UNITED STATES PATENT OFFICE.

SAMUEL LIPSIUS, OF NEW YORK, N. Y.

AUTOMATIC POWDERING MACHINE.

Application filed August 6, 1926. Serial No. 127,506.

This invention relates to apparatus for producing raised printing. In connection with the methods of printing with which such apparatus is used the desired copies 5 are printed on sheets, suitable powder is applied to the printed sheets, the excess powder is removed from the printed portions of the sheets, and the sheets are then baked so as to fix or set the powder. The 10 powder employed is of a largely resinous or shellac-like nature and inasmuch as it is very finely divided, it is quite difficult to handle and has a tendency to lump and become sticky particularly in damp and warm 15 weather so that it is extremely difficult to apply the powder where desired and even more difficult to remove it from places where it is not desired.

An important object of the present invention is to provide simple and effective apparatus to meet the requirements for such work.

Other objects of the invention are to provide apparatus of the character described 25 which can be operated at high speed and with a minimum of supervision; apparatus in which the excess powder is removed at a plurality of positions along the path of the sheets through the apparatus; apparatus 30 in which the sheets are carried by an open work conveyer and comprising a device for blowing the excess powder from the sheets at a certain position in their path and a baffle member located immediately beneath 35 the upper reach of the conveyer belt at the powder removing position so as to control the air currents irrespective of the presence or absence of sheets at said powder removing position; and apparatus in which 40 the excess powder is removed from the sheets at a plurality of positions along their path by blowing devices and substantially the same amount of air as supplied by the blowing devices is sucked up at such removing 45 positions to avoid sifting of the powder outside the apparatus.

In carrying out the invention which utilizes certain principles of some of my prior 50 patents and of my co-pending application Serial No. 69,283, Nov. 16, 1925, of which this is a partial continuation, I provide a wire mesh belt which serves to convey through the apparatus in a generally horizontal direction, sheets which have been 55 printed with suitable ink. The printed sheets may be deposited on the conveyer by hand or automatically from a printing press, a chute being provided in the latter case to receive the printed sheets and discharge them on the conveyer. Mounted above the 60 conveyer is a feeding device comprising a hopper from which the embossing powder is discharged upon the sheets as they pass beneath it. Preferably the hopper is provided with one or more metal sheets or plates supported so as to permit vibration thereof and serving to control the passage of the powder from the hopper. I also provide a device by which the edge of one of the plates or sheets is operated upon so as to 65 produce vibrations in the metal sheet and insure the passage from the lower end of the hopper of a fine thin stream of powder uniformly and without sticking or clogging. After the powder has been deposited on 70 the sheets, the latter are subjected to treatment for removing the excess of powder. Such removal may be accomplished, for example, by means of air blasts. Beneath the conveyer there is a receptacle for receiving 75 powder which has not adhered permanently to the sheets and has passed downwardly below the conveyer. This powder passes to the bottom of the receptacle and is reconveyed to the hopper by suitable means, such as a belt or chain having buckets, from 80 which it is discharged into the hopper.

It is of considerable importance to control the powder blown from the sheets for, if the extremely fine powder ordinarily employed be not controlled, it would be blown and sifted outside of the machine and would both inconvenience the operators and cause a waste of the powder. To avoid such waste there may be provided a housing for the 90 hopper and the conveyer, and suction means including intakes located above the conveyer adjacent the positions at which the excess powder is blown from the sheets. Preferably the arrangement is such that the air 100 supplied by the blowers is taken up by the suction intakes and again returned through the blowing devices. The invention also includes means for holding the sheets on the conveyer against the action of the suction 105 means. It has also been found important to place baffle members or plates beneath the upper reach of the conveyer immediately beneath the powder removing positions so that in case no sheet is in position on the 110 conveyer belt at this point, the air from the blower will not pass freely through the con-

veyer belt but will be deflected upwardly by the baffle plate and the normal circulation of air will not be disturbed. It will be seen that this arrangement also prevents 5 any abnormal sucking up of air from beneath the conveyer under such conditions. As the sheets pass from the apparatus they may be discharged on a conveyer leading to a usual heater or oven for fixing or setting 10 the powder.

In the drawings

Fig. 1 is a longitudinal vertical sectional view on the general plane of the line 1—1 of Fig. 2.

15 Fig. 2 is an end view partially in section.

Fig. 3 is a detail view illustrating the devices used to hold the sheets down on the conveyer beneath the suction intakes; and

20 Fig. 4 is a sectional view of the structure shown in Fig. 3.

The sheets to be powdered may be deposited on a woven wire mesh or foraminous conveyer belt 5 supported and driven in any suitable manner, as for example, by means 25 including rollers of which the roller 6 at the right in Fig. 1 is supported by a shaft 7 carrying pulleys 8 and 9. The first pulley 8 is connected by a belt 10 with a pulley 11 on a shaft 12 mounted in the lower part of 30 the frame. Power may be supplied to the shaft 12 by means of a motor 13 having a pulley 14 connected by a belt 15 with a pulley 16 on a shaft 17, power being transmitted from the shaft 17 to the shaft 12 by means 35 of a belt 18 mounted at one end on a pulley 19 on the shaft 17 and at the other end on a pulley 20 on the shaft 12.

40 The powder is placed initially in a receptacle 21 which is located at a lower level than the conveyer and at one side of the machine or the powder may be placed in a hopper 22 above the conveyer and extending entirely across the same. In the hopper 22 there are inclined plates 23 and 24 which extend through a narrow slot at the bottom of the hopper 22 and serve to control the discharge of the powder. These plates are 45 resilient and should be quite stiff as well as perfectly straight along their meeting line at the bottom of the hopper. Preferably both of the plates 23 and 24 are vertically adjustable, the plate 23 to vary the permissive opening at the bottom of the hopper and the plate 24 for reasons to be mentioned 55 hereinafter. Such adjustment may be obtained by means of bolt and slot connections between the plates 23 and 24 and the corresponding walls of the hopper 22, the release and tightening of the plates 23 and 24 being 60 obtained by means of wing nuts 25 and 26 respectively. The plate 24 is secured quite rigidly to the hopper at its upper end and the connection is such that it may act as a spring plate, the discharge of the powder 65 being affected by vibrating the plate 24.

Such vibration of the plate 24 is obtained by means of a shaft 27 suitably located beneath the hopper and provided with one or more shoulders which serve to engage the lower edge of the plate 24 and set it into vibration 70 at intervals as the shaft 27 is rotated. The discharge slot 28 may be approximately from 1/16 to 3/16 of an inch wide. As a result of the vibration of the plate 24 the powder in the hopper is sifted through the 75 slot continuously in a very fine or thin stream. The actuation of the shaft 27 may be obtained by belt 29 extending around a pulley 30 on shaft 27 and around the pulley 9 30 on shaft 7.

Powder in the receptacle 21 may be raised therefrom by a suitable bucket-type conveyer 31 which is mounted on upper and lower shafts 32 and 33 respectively, the upper shaft 32 being driven by means of a pulley 34 thereon and a belt 35 also engaging a pulley 36 on the shaft 17. As the powder is thrown from the conveyer 31, it passes into a discharge head 37 from which it passes into the hopper 22. To insure uniform distribution, the discharge head 37 is provided with one or more suitable partitions 38.

Beneath the conveyer belt 5 there is a chute 39 with inclined walls leading to the powder receptacle 21 so that the powder 95 discharged from said hopper and passing downwardly through the conveyer belt 5 is returned to the receptacle 21. The chute 39 may be provided with baffles 40 which tend to guide the powder passing downwardly 100 from the hopper and through the conveyer belt 5, more directly into the receptacle 21. Frequently there is a tendency for the powder to collect at the lower end of the chute 39 in such a way as to block the entrance 105 thereof into the receptacle 21 and for the purpose of preventing such action, there may be provided a link 41 having its upper end attached eccentrically to a shaft 42 having thereon a pulley 43 which is connected by 110 means of a belt 44 with a pulley 45 on the shaft 17.

In the form of apparatus shown herein I provide air blast means for removing the excess or surplus powder from the sheets on 115 the conveyer belt 5. Such air blast may be provided by an air pump or blower 46 driven by any suitable source of power but preferably by an individual motor 47 connected therewith, the blower 46 and the motor 47 being mounted on the upper part of a hood 48 extending over the hopper 22 and the greater portion of the conveyer belt 5. As here shown, the outlet 49 from the blower 46 is divided into two branches 120 50 and 51 which are connected at their lower ends with discharge or blower pipes 52 and 53 respectively. The discharge pipes 52 and 53 are provided with discharge openings 54 and 55 respectively so positioned 130

that the air blast in each case will blow the powder rearwardly beneath the inlets of suction pipes 56 and 57 respectively which converge into a single pipe 58 leading to the inlet portion of the blower 46. It will be seen that the air expelled through said openings 54 and 55 will be drawn upwardly through said suction pipes 56 and 57 and after passing through the blower 46 will again be expelled through the openings 54 and 55. By this arrangement undue disturbance of the air is prevented and powder is prevented from sifting to the outside of the apparatus.

15 To hold the sheets in position on the conveyer belt 5 while passing beneath the lower ends of the suction pipes 56 and 57, provision is made of sets of rollers 59 and 60 preferably formed of rubber and with bevelled edges so as to engage only a small portion of the sheets passing thereunder. As shown in Fig. 3 the rollers or discs 59 are provided with central openings 60 of greater diameter than the diameter of the supporting shaft 61 so that when the shaft 61 is suitably spaced with reference to the conveyer belt, the only pressure exerted by the roller 60 will be that due to the weight of the rollers. To obtain the proper spacing 25 of the rollers or discs 59 use is made of spacing sleeves 62. The rollers or discs 60 are mounted in substantially the same way as rollers or discs 59.

30 It has been found that very much better results are obtained by locating baffle members or plates 63 and 64 beneath the upper reach of the conveyer belt 5 and below the lower ends of the suction pipes 56 and 57 respectively. It will be apparent that the baffle members or plates 63 and 64 tend to render the action of the air currents substantially the same regardless of the movement of the sheets past their powder removing positions, thus insuring substantially 35 uniform operation at all times.

I provide a metal chute 65 between the wire mesh conveyer 5 and the printing press from which the sheets are advanced by a conveyer 66 to the chute 65. By separating the belt 66 from the conveyer belt 5 in this way, powder from the powdering device is prevented to a greater extent from collecting on the conveyer 66. This matter has been found to be very important since otherwise in a day's run a very considerable amount of powder might be carried back to the printing press where it would interfere very much with the satisfactory operation of the apparatus. Obviously, the chute 65 may readily be cleaned.

It will be seen that the apparatus of the present invention is simple in construction and operation, compact in form, and capable of handling large as well as small sheets 65 at a high rate of speed. Furthermore, the

powdering device is such as to make it possible to apply the ordinary commercial embossing powders uniformly and economically under all conditions of humidity. Also the means for removing the excess powder 70 and controlling the air currents insures not only a uniform distribution of the powder on the sheets and the complete removal of all excess powder but saves all of the powder which is not required for the embossing 75 effect and prevents undesirable collection of the powder in various parts of the machine.

It will be apparent that substantially the same amount of air is taken up by the suction pipes 57 and 58 as is expelled through the openings 54 and 55 of the pipes 52 and 53. Under some conditions, however, the pressure in the hood 48 may be increased 80 to an undesirable extent. In order to prevent such increase of pressure in the hood 48 it may be desirable to provide suitable openings 67. One disadvantage of undue increase of pressure in the hood 48 would be that powder might be blown out under 85 the front and rear edges of the hood. From the delivery end of the apparatus shown, the sheets may pass over a chute 68 to a conveyer 69 of a heating or baking device in which the powder is fixed or set.

It should be understood that the embodiment of the invention herein disclosed is merely illustrative and that various changes may be made in the arrangement and construction of various parts without departing from the true spirit and scope of the invention.

Having thus described my invention, I claim:

1. In apparatus of the character described, sheet-conveying means comprising a foraminous belt for supporting the sheets, means for distributing powder on said sheets, excess-powder-removing means including an air blast device, and a baffle immediately beneath the upper reach of said belt to control the air currents when no sheet is present at said position.

2. In apparatus for producing raised printing, sheet-conveying means, means for distributing powder on sheets advanced by said conveying means, means for blowing excess powder from said sheets at a certain position along their path, a baffle beneath said path at said position and a device having its intake adjacent the path of said sheets above said baffle and adapted to carry off the air supplied by the blowing means.

3. In apparatus of the character described, sheet-conveying means, means for distributing powder on sheets advanced by the conveying means, a plurality of blowing devices arranged at different positions along and each extending across the path of said sheets to remove powder from said sheets,

means for carrying off the air supplied by said blowing devices and comprising an inlet extending across the conveying means adjacent each of said powder removing devices, each inlet between blowing devices extending substantially from one to the other, and baffle plates beneath the path of said sheets and adjacent the blowing devices.

5 4. In apparatus of the character described, sheet-conveying means comprising a foraminous belt for supporting the sheets, means for distributing powder on said sheets, excess-powder-removing means including an air blast device, a suction device 10 having an inlet adjacent the path of said sheets at the position where said air blast device acts on said sheets, and a baffle immediately beneath the upper reach of said belt to control the air currents when no 15 sheet is present at said position.

10 5. In apparatus of the character described, a foraminous sheet-conveying belt, a hood over the upper run of the belt, powder-applying means including a hopper 15 above the conveying belt, air blast means for removing excess powder from the sheets, a chute to receive powder passing downwardly through the belt and extending the full length of the belt, and baffle means in 20 said chute including two baffles immediately beneath and at opposite sides of said hopper to guide powder passing through said belt directly below said hopper down to the bottom of the chute and to prevent the blowing 25 of powder out of the inlet end of the apparatus.

40 6. In apparatus of the character described, a foraminous sheet-conveying belt, means for distributing powder on sheets carried by said belt, excess-powder-removing means including an air blast device blowing the excess powder rearwardly, means for engaging the upper surfaces of sheets just before they reach the powder removing 45 position and holding the sheets against the upper side of the belt while the air blast is removing the excess powder and suction means for carrying off the removed excess powder.

50 7. In apparatus of the character described, a sheet-conveying belt, means for distributing powder on sheets carried by said belt, excess-powder-removing means including an air blast device extending across 55 the belt and blowing the excess powder rearwardly, a suction device having an inlet at the rear of said air blast device, and a baffle beneath the upper run of the belt adjacent the air blast device, and anti-friction means 60 for engaging the upper surfaces of the sheets after they are moved above the baffles and serving to hold the sheets against the upper side of the belt.

8. In apparatus of the character described, a foraminous sheet-conveying belt,

powder applying means, excess-powder-removing means acting on said sheets after receiving powder thereon, a chute with converging walls to receive the powder passing downwardly through the belt and means to prevent clogging of the lower end of said chute, including a crank in said chute and a link loosely connected therewith.

9. In apparatus of the character described, a sheet-conveying belt, means for distributing powder on sheets carried by said belt, excess-powder-removing means including an air blast device extending across the belt and blowing the excess powder rearwardly, suction means having an inlet extending across the belt at the powder removing position and at the rear of the air blast device, and means for engaging the upper surfaces of cards just before they reach the powder removing position and holding the sheets against the upper run of the belt.

10. In apparatus of the character described, sheet-conveying means, and means for distributing powder on the sheets as they advance comprising a hopper above the path of said sheets, a resilient plate in said hopper having a free edge, and means for engaging said free edge and causing the plate to vibrate thereby agitating the powder in said hopper and causing the powder to flow.

11. In apparatus of the character described, sheet-conveying means, and means for distributing powder on the sheets as they advance comprising a hopper above the path of said sheets, a resilient plate in said hopper rigidly secured at its upper edge and extending downwardly through the outlet of the hopper, and means for engaging the lower edge of the plate and causing the plate to vibrate.

12. In apparatus of the class described, sheet-conveying means, and means for distributing powder on said sheets as they advance comprising a hopper having a narrow outlet extending across the conveying means, resilient plates secured at their upper edges and extending downwardly through said outlet to control the passage of said powder, and means for vibrating one of said plates.

13. In apparatus of the character described, sheet-conveying means, and means for distributing powder on the sheets as they advance comprising a hopper above the path of said sheets, a resilient plate in said hopper and having a free edge extending through an opening in the bottom of the hopper, and means for engaging said free edge and causing the plate to vibrate, thereby agitating the powder in said hopper and causing the powder to flow.

14. In apparatus of the character described, sheet-conveying means, and means for distributing powder on the sheets as they advance comprising a hopper above the path

of said sheets, a resilient plate vertically adjustable in said hopper and extending downwardly through the outlet of the hopper, and means for engaging the lower edge of the 5 plate and causing the plate to vibrate.

15. In apparatus of the class described, sheet-conveying means, and means for distributing powder on said sheets as they advance comprising a hopper having a narrow 10 outlet extending across the conveying means, upwardly and downwardly adjustable resilient plates secured at their upper edges and extending downwardly through said outlet to control the passage of said powder, and 15 means for vibrating one of said plates.

16. In apparatus of the character described, sheet-conveying means; means for distributing powder on the sheets as they advance, comprising a hopper above the 20 path of said sheets, a resilient plate in said hopper and having a free edge extending through an opening in the bottom of the hopper, and means for engaging said free edge and causing the plate to vibrate; a 25 chute to receive powder falling below said sheet-conveying means; and means to raise said powder from the bottom of said chute and deliver it into said hopper.

17. In apparatus of the character described, sheet-conveying means; means for distributing powder on the sheets as they advance, comprising a hopper above the path of said sheets, a resilient plate in said hopper and having a free edge extending 30 through an opening in the bottom of the hopper, and means for engaging said free edge and causing the plate to vibrate; a chute to receive powder falling below said conveying means; and means to raise said 35 powder from the bottom of said chute and deliver it into said hopper, and including means to distribute the powder along the 40 length of said hopper.

18. In apparatus of the character described, a foraminous sheet-conveying belt; means for distributing powder on sheets conveyed by said belt and comprising a hopper having a narrow outlet extending across the conveying means, upwardly 45 and downwardly adjustable resilient plates secured at their upper edges, and means for vibrating one of said plates; excess-powder-removing air blast devices arranged at different points along the upper reach of 50 said belts, suction means including inlets arranged just above said belt at the baffles beneath the upper reach of said belt at the powder-removing points, a chute beneath 55 said belt to receive powder dropping there- 60 through, an agitator in said chute to prevent clogging at the outlet thereof, baffles in said chute to guide to the bottom of the chute powder dropping directly through said belt from the hopper, a hood over the top of said 65 machine and having perforations at the top

thereof, means to convey the powder from the bottom of said chute to the upper part of said hood, and a distributor in said hood receiving powder from such conveying means and delivering the powder into the hopper. 70

19. A sheet powdering machine comprising a sheet conveyer, a powder receptacle below the conveyer, a hopper above the conveyer, a distributor adapted to receive powder at one side of the machine and having 75 at a lower level a mouth extending longitudinally of the hopper and a plurality of downwardly inclined partitions to assist in guiding the powder to different points along the hopper and means for raising powder 80 from said receptacle to said distributor.

20. A sheet powdering machine comprising a foraminous sheet conveyer, a powder receptacle below the conveyer, a hopper above the conveyer, vibrating means in said 85 hopper to automatically agitate the powder therein, a distributor extended across said hopper, means for raising powder from said receptacle to said distributor, a hood enclosing most of the upper run of the conveyer, 90 and suction means connected with said hood.

21. A sheet powdering machine comprising a foraminous belt sheet conveyer, a powder receptacle below the conveyer, a hopper above the conveyer, a distributor having a plurality of inclined channels extending over said hopper to different points, a suction device for removing floating particles of powder and returning them to said receptacle 100 and means for raising powder from said receptacle to said distributor.

22. In a sheet powdering machine, a conveyer, a powder hopper having two resilient plates overlapping each other above said 105 conveyer, one of said plates being adjustable with reference to the other to vary the possible separation of their adjacent edges and automatic means for intermittently and rapidly engaging a free edge of one of said 110 plates to effect vibration and to feed the powder uniformly from said hopper.

23. In a sheet powdering machine, a sheet conveyer, a hopper, and means for distributing powder on sheets on said conveyer including a movable inclined partition at one side of said hopper having its lower end projecting below the hopper and a rotating shaft having means thereon for intermittently engaging said lower end for rapidly 115 vibrating said partition and thereby move said end away from the stationary part of the hopper to intermittently deposit powder. 120

24. A sheet powdering machine comprising a foraminous sheet conveyer belt, a powder receptacle below the conveyer, a hopper above the conveyer and having a resilient plate rigidly secured at one edge, the opposite edge being arranged close to a stationary edge of the hopper, means for vi- 125 130

brating said plate to intermittently form and close an opening, a distributor extending across said hopper, means for raising powder from said receptacle to said distributor, means for removing excess powder from the sheets on said conveyer, and a hood enclosing most of the upper run of said sheet conveyer.

25. In a sheet powdering machine, a conveyer, a powder discharging hopper with converging sides above the conveyer and having a narrow slot at the bottom extending across the conveyer, a vibrating member in said hopper and between the walls thereof of forming one edge of a discharge opening for agitating the material in the hopper and opening and closing the discharge opening, and means for automatically vibrating the vibrating member from outside the hopper.
26. A sheet powdering machine comprising a foraminous belt conveyer having a horizontal run for supporting the sheets to be powdered, a hopper arranged with a narrow outlet extending across the conveyer near one end, means for dislodging excess powder from the sheets on the conveyer, a collecting chute having its upper end extending beneath substantially the entire upper run of the conveyer below the hopper and the powder dislodging means and having its walls converging downwardly to a point at one side of the machine beneath the hopper, a powder lifting conveyer dipping into the bottom of said chute at the side thereof and having a housing extending up along one side of the machine, a distributor ex-

tending from the upper end of said lifting conveyer and its housing to the upper end of the hopper, a hood enclosing said hopper, said dislodging means and said distributor. 40

27. A powdering machine comprising a conveyer belt, a hopper for delivering a narrow stream of powder across the belt, a collecting chute beneath the belt, a lifting conveyer and distributor for returning the unused powder from said chute to the hopper, a suction blower having an outlet for ejecting a stream of air on to the top of the belt for dislodging excess powder, said suction blower having a suction inlet adjacent the blower outlet for immediately picking up the floating particles of powder from the air above the belt and returning such particles with the dislodging stream of air and a hood enclosing said hopper, said distributor, 55 said blower outlet and said suction inlet.

28. In a powdering machine, a foraminous travelling conveyer belt, a hopper having an outlet above the belt for depositing a thin layer of powder as sheets are carried under it by the conveyer, a blower having an outlet arranged close to the upper run of the conveyer for removing excess powder from the sheets, a suction pipe having an inlet immediately adjacent the blower outlet and close to the conveyer, a hood surrounding the outlet of the hopper, the outlet of the blower and the inlet to the suction pipe, means for collecting the unused powder and means for returning the collected powder to the hopper. 60 65

SAMUEL LIPSIUS.
